SUGAR BOWL

Paul P. Miano, Box 246, Garyville, La.

Filed Aug. 14, 1959, Ser. No. 57,184

Term of patent 14 years

(Cl. D44—15)

Fig. 1

Fig. 3

Fig. 1 is a perspective view of a sugar bowl, showing my new design;

Fig. 2 is a top plan view thereof; and

Fig. 3 is an elevational view of the same.

I claim:

The ornamental design for a sugar bowl, as shown.
